HEADREST FOR AN AUTOMOBILE SEAT

Werner C. Apel, Rte. 1, Imperial, Mo.

Filed Feb. 4, 1963, Ser. No. 73,434

Term of patent 3½ years

(Cl. D15—8)

FIG. 1

FIG. 2

FIG. 3

FIG. 4

FIG. 5

FIG. 1 is a side elevational view of my headrest, shown in place on a typical car seat, the seat being shown in dotted lines for illustrative purposes only, the opposite side of my invention being a mirror image of FIG. 1;

FIG. 2 is a top plan view thereof;

FIG. 3 is a bottom plan view thereof;

FIG. 4 is a rear elevational view thereof; and

FIG. 5 is a front elevational view thereof.

I claim:

The ornamental design for a headrest for an automobile seat, as shown and described.
